HOOD FOR COVERED SURFACE BOWLING BALL RETURN

George E. Schaefer, Muskegon, Mich., and Richard G. Reineman, Balboa, Calif., assignors to The Brunswick Corporation, Skokie, Ill.

Filed Nov. 20, 1970, Ser. No. 26,095

Term of patent 14 years

Int. Cl. D21—02
U.S. Cl. D34—5

FIG. 1 is a perspective view of the hood of our design taken from about left and to the rear.

FIG. 2 is a side view of the hood of our design.

FIG. 3 is a back view of the hood of our design.

FIG. 4 is a front view of the hood of our design.

We claim:

The ornamental design for a hood for covered surface bowling ball return, substantially as shown.
